CLAIM

(52) U.S. Cl. **D12/555**

The ornamental design for an automobile tire, as shown and
described.

(58) Field of Search D12/134-152;
152/209.1, 209.3, 209.9, 209.13, 209.25,
209.28

DESCRIPTION

(56) **References Cited**

FIG. 1 is a front perspective view of an automobile tire
showing my new design, it being understood that the tread
design is repeated uniformly throughout the circumference
of the tire;

D389,790 S 1/1998 Himuro
D400,140 S 10/1998 Graas
D416,836 S * 11/1999 Himuro D12/147
D418,782 S * 1/2000 Williams D12/147
6,213,180 B1 * 4/2001 Himuro 152/209.28

FIG. 2 is a front elevational view thereof;
FIG. 3 is a rear elevational view thereof;
FIG. 4 is a right side view thereof; and,
FIG. 5 is a left side view thereof.

In the drawings, the dark stippled surface shading represents
the recessed portion of the tread grooves, having a depth as
best shown at the top and bottom edges of FIGS. 2 and 3.
